HOCKEY GAME BOARD

Allan Peters, Sherman Oaks, Calif.

Application July 24, 1958, Serial No. 51,921

Term of patent 14 years

(Cl. D34—5)

FIG. 1

FIG. 2

FIG. 3

FIG. 4

Fig. 1 is a top plan view of a hockey game board, showing my new design;

Fig. 2 is a perspective view thereof showing the near ball return gate in open position;

Fig. 3 is another perspective view thereof; and
Fig. 4 is a bottom perspective view.

I claim:

The ornamental design for a hockey game board, substantially as shown and described.
